UNITED STATES PATENT OFFICE.

JESSE WASHINGTON PIERCE, OF BELTON, TEXAS.

CAN-OPENER.

SPECIFICATION forming part of Letters Patent No. 707,253, dated August 19, 1902.

Application filed November 20, 1901. Serial No. 83,051. (No model.)

To all whom it may concern:

Be it known that I, JESSE WASHINGTON PIERCE, a citizen of the United States, residing at Belton, in the county of Bell and State of Texas, have invented a new and useful Can-Opener, of which the following is a specification.

This invention relates to can-openers of that character embodying a fulcrum-point to be inserted into the center of the head of a can and about which the device is adapted to be swung, so as to cut the head of the can in the path of a circle. In this type of can-opener considerable difficulty is experienced in thrusting the fulcrum-point of the can-opener into the top of the can, and in view of this difficulty it is the object of the present invention to arrange the stem and handle of the device so that the latter may be employed as a driver to force the pointed end of the stem into the head of the can, thereby to facilitate the engagement of the device with the can.

With this and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view of a can-opener embodying the present invention and shown in position to cut the head of a can. Fig. 2 is a longitudinal sectional view of the can-opener, illustrating the manner of driving the pointed stem. Fig. 3 is a cross-sectional view taken on the line 3-3 of Fig. 2. Fig. 4 is a detail perspective view of the stem of the device.

Like characters of reference designate corresponding parts in all the figures of the drawings.

Referring to the accompanying drawings, 1 designates the metallic stem, which is provided at its outer end with a lateral extension 2, terminating in a forwardly-directed terminal pointed projection 3, thereby forming a pointed hook-terminal. Upon this stem

there is slidably mounted a heavy metallic handle 4, which is tubular in form to receive the stem and is provided with a transverse pin or key 5, which works in a longitudinal slot or groove 6, formed in the stem, thereby to prevent turning of the handle upon the stem and also to limit the endwise movement of the handle. The inner end of the handle 60 is provided with a reduced cylindrical extension 7, upon which is rotatably mounted a cutting-disk 8, which is held in place by means of a washer 9, fitted to the cylindrical extension and against the outer face of the 65 disk, the outer end of the extension being upset against the disk, as indicated at 10, whereby the disk is rotatably mounted upon the handle.

In using the can-opener the point 3 is placed 70 at the center of the head of a can, after which the handle is withdrawn to its outer limit and then quickly thrust downwardly, whereby the pin 5 strikes against the lower shoulder of the slot or groove 6 in the stem, and thus 75 forces the pointed end of the latter into the can, after which the handle is swung downwardly, so as to bring the cutting-disk into engagement with the can, and then the device is swung around upon the point of the 80 stem as a fulcrum, thereby to cut the head of the can in the path of a circle.

From the foregoing description it is apparent that the present device is adjustable to accommodate the same to cans of different 85 diameters, as the handle is slidable upon the stem, and therefore the cutter may be located at any point upon the stem within the limit of the handle. Furthermore, by reason of the fact that the inward movement of the 90 handle upon the stem is positively limited by reason of a portion of the handle striking against the stem the handle forms a driver, which can be conveniently manipulated to facilitate the driving of the pointed end of 95 the stem into the head of a can.

What I claim is—

1. A can-opener, comprising a pointed stem, a freely-reciprocatory weighted driving-handle slidably mounted upon the stem, a stop engagement between the stem and the handle to limit the inward movement of the latter, and a cutter carried by the handle.
2. A can-opener, comprising a pointed stem

having a longitudinal slot or groove, a freely-reciprocating weighted driving-handle slidably mounted upon the stem and having a projection working in the slot or groove for contact with the opposite ends thereof, and a cutter carried by the handle.

3. A can-opener, comprising a stem provided at its outer end with a hooked pointed terminal, and also having an intermediate longitudinal groove or slot, a hollow metallic handle slidably mounted upon the stem, and provided with a transverse pin working in the slot or groove and adapted to engage the opposite ends thereof, the inner end of the handle being reduced, and a rotatable cutting-

disk mounted upon the reduced inner end of the handle, the outer end of the reduced portion of the handle being upset to prevent displacement of the disk.

4. A can-opener, having weighted freely-reciprocating means working upon the stem thereof and forming a driving-handle to drive the point of the stem into a can.

In testimony that I claim the foregoing as my own I have hereto affixed my signature in the presence of two witnesses.

JESSE WASHINGTON PIERCE.
